UNITED STATES PATENT OFFICE.

ARTHUR B. MODINE, OF RACINE, WISCONSIN.

TEMPERATURE-CONTROL SYSTEM FOR INTERNAL-COMBUSTION ENGINES AND THE LIKE.

Application filed December 29, 1919. Serial No. 348,243.

To all whom it may concern:

Be it known that I, ARTHUR B. MODINE, a citizen of the United States, residing at Racine, in the county of Racine and State 5 of Wisconsin, have invented certain new and useful Improvements in a Temperature-Control System for Internal-Combustion Engines and the like, of which the following is a description.

10 My invention relates to means for controlling the temperature of the circulating liquid for internal combustion motors and the like.

The object of my invention is to provide a simple, reliable and efficient device for 15 regulating the passage of the cooling medium through the radiator of an internal combustion engine to correspond with variations in temperature of the circulating medium.

20 To this end my invention consists in the novel construction, arrangement and combination of parts herein shown and described and more particularly pointed out in the claims.

25 In the accompanying drawings wherein like or similar reference characters indicate like or corresponding parts;

Fig. 1 is a front elevation of a radiator equipped with my improvement.

30 Fig. 2, is a side elevation of the same with parts removed and broken away to more clearly show the construction.

Fig. 3 is a view similar to Fig. 1 showing a slightly modified form of my improvement.

35 Fig. 4 is a side elevation of the form of my device shown in Fig. 3.

In the form shown in Figs. 1 and 2 1 is a radiator of the usual or any preferred 40 form adapted to contain a circulating liquid and having the usual plurality of transverse openings or cells therethrough, through which the air or other cooling medium passes to cool said circulating liquid, 45 said radiator preferably having the core 2 slightly set back from the face of the tanks or reservoirs 3 and 4 at the top and bottom of the radiator respectively. A flexible curtain or screen 5 is provided at the front of 50 the radiator wound upon a roller 6 which is in turn mounted upon the brackets 7 and 8 at the respective sides of the radiator, the curtain 5 being preferably of sufficient width to cover the entire face of the core and 55 slightly over-lap the side margins 9 and 10

of the shell or housing to effectively cut off the air from that portion of the radiator which may at any time be covered by the curtain 5.

In the preferred construction a roller 6 60 is provided with a spring 11 adapted to normally tend to rotate the roller to wind the curtain on to the roller or in other words draw the curtain or screen downward onto the roll thus exposing the entire surface of the radiator. Any suitable means may be provided to control the position of the curtain to correspond with the temperature of the liquid in the radiator. As shown a tubular chamber 12 is provided in the 70 lower reservoir 4 of the radiator with a portion 14 extending upward through the horizontal wall projecting at the lower margin of the core 2 and a plunger 15 is positioned in the part 14 adapted to move longitudinally thereof so that when the chamber 12 is filled with liquid having a suitably high coefficient of expansion the position of the plunger 15 will be controlled by the temperature of the liquid in the chamber. 75 Liquefied gases have an extremely high coefficient of expansion and may be used if so desired. The several parts are so proportioned and the amount of liquid in the chamber is so arranged that when the liquid 80 is cold or nearly so the plunger 15 will stand at the lower limit of its movement and as the temperature of the liquid in the chamber increases the expansion of the liquid will force the plunger upward. If 85 desired, a diaphragm may be interposed between the plunger and liquid, in order to provide a greater expansive effort upon the plunger.

Any suitable means may be provided for 90 connecting the plunger and curtain so that the movement of the plunger will produce a corresponding movement of the curtain. In the form shown a pair of sheaves 16 are provided at the upper end of the plunger and 100 a pair of similar sheaves 17 are attached to the upper portion of the radiator as to the reservoir 3 and a cord 18 or other flexible means is attached to the upper edge of the curtain and passes first over one of the 105 sheaves 17 thence under one of the sheaves 16 thence back and over one of the sheaves 17 and thence around the second sheave 16 and with its opposite end rigidly attached to the upper portion of the radiator so that

a comparatively slight movement of the plunger will produce a considerable movement of the curtain. A pair of springs 19 are also provided extending from a suitable cross-arm 20 or other suitable means upon the plunger to the lower portion of the radiator to normally hold the plunger at the lower limit of its movement slightly more than counterbalancing the spring 11 upon the roller. When thus constructed and arranged it is obvious that when the liquid in the chamber 12 is cold the curtain 5 will substantially cover the face of the radiator preventing the circulation of air or other liquid therethrough. As the temperature of the radiator increases the temperature of the liquid in the chamber 12 will correspondingly increase, thus moving the plunger upward and permitting the spring 11 to wind the curtain 5 on to the roller 6 thereby gradually uncovering the face of the radiator and permitting the cooling fluid to circulate therethrough; thereby progressively increasing the area of the section of the radiator covered by the curtain to correspond with the decrease or increase of the temperature of the circulating fluid in the radiator.

In the form shown in Figs. 3 and 4 the radiator and associated parts may be of the usual or any preferred construction. In this form however the curtain or screen 21 is preferably a rigid plate pivotally attached to the radiator housing or other convenient portion of the radiator mechanism at one margin of the core as at 22 and a link 24 is pivotally connected as at 25 near the opposite margin of the core with the free end of the link bifurcated and pivotally connected to suitable lugs or brackets 26 at an intermediate portion of the plate, the extremities of the forked ends of the link being preferably slotted at 27 or otherwise connected to the lugs to permit free movement between the lugs and the link. The motor chamber 28 in this form is positioned within the upper reservoir of the radiator with a part 29 projecting through the front face thereof and a plunger 30 is positioned in the part

29 and connected to the link 24 as at 31 to control the movement of the link so that as the temperature of the liquid in the chamber increases the plunger 30 will be forced outward thereby swinging the lower end of the link outward with the upper portion of the curtain 21 and thereby decreasing the section of the radiator covered by the curtain, the operation being substantially as hereinbefore described.

Having thus described my improvement it is obvious that various immaterial modifications may be made in my device without departing from the spirit of my invention, hence I do not wish to be understood as limiting myself to the exact form of construction shown.

What I claim as new and desire to secure by Letters Patent is:

In a temperature control system, a radiator for containing a circulating liquid and provided with a plurality of transverse openings for permitting the passage of a cooling medium therethrough, in combination with a flexible movable screen for arresting the passage of said medium through the openings in a certain section of said radiator, a support for said screen whereby it may be coiled, spring means tending to coil said screen to increase the area of said section, means partially surrounded by said liquid and controlled by the temperature thereof for operating said screen to progressively decrease the area of said section a unit amount with any incremental increase in the temperature in the circulating liquid, said operating means comprising a plunger, a casing surrounding said plunger, and spring means slightly overbalancing the effect of said first mentioned spring means and tending to return the plunger to its inoperative position in said casing.

In testimony whereof I have hereunto signed my name in the presence of two subscribing witnesses.

ARTHUR B. MODINE.
